INDEX TAB

Walter T. Gollwitzer, Cleveland, Ohio, assignor
to Addressograph Company, Cleveland, Ohio,
a corporation of Delaware

Original application May 23, 1932, Serial No.
612,957. Divided and this application November
7, 1935, Serial No. 48,670

7 Claims. (Cl. 129—16.8)

My prior application No. 612,957, filed May 23rd, 1932, of which this application is a division, shows and describes a novel index tab and one form of address plate frame on which the same may be mounted, and claimed the tab, the frame, and the combination thereof. My later application No. 703,899, filed December 26th, 1933, shows the same tab applied to a different form of addressing device and operated in a somewhat different manner, and claims that addressing device and the tab combined therewith.

The present application is concerned with the tab itself, whether used in the combination of either of said prior applications or in some other combination. The claims of this application are taken from application 612,957, where they have been held allowable.

The tab comprising the present invention is adapted to be readily inserted in any one of a number of keepers on the device to be indexed, and when so inserted will be automatically locked in place, but may be very readily released and removed whenever desired. It may be stated, therefore, that the general object of the invention is to provide a simple index tab having these characteristics.

More particularly, it is an object to provide the tab of such a character that it may be inserted either face forward, thus simplifying the matter of insertion if both faces are alike, and, on the other hand, doubling the indicating value of the tab if the opposite faces are different, as, for instance, of different colors. Another object is to provide a tab which will not become tangled with other tabs when lying loosely in a receptacle.

I accomplish the desired results by providing a tab on the shank of which is a tongue projecting toward the body of the tab and having sufficient spring action so that it will normally lie in the plane of the tab or return thereto when free, but may be readily forced out of such plane and thus become a projecting barb registering with a retaining shoulder on the member to be indexed.

As illustrated in the drawing hereof, and as hereinafter claimed, the diversion of the tongue from its normal plane may be effected consequent upon the insertion of the tab into the keeper of the member to be indexed, thus automatically locking the tab upon insertion, while thereafter the tab may be readily freed by a slight manual pressure against the tongue, pressing it back into the plane of the tab.

My tab is illustrated in the drawing hereof, which also shows the tab mounted in addressing

devices respectively of the character of the two applications mentioned. In the drawing, Fig. 1 is a perspective of the tab itself; Fig. 2 is a face view of an address plate frame with two of the tabs mounted thereon, this frame being in accordance with my application 612,957; Fig. 3 is a fragmentary rear view of the frame of Fig. 2; Fig. 4 is an enlarged cross-section on the line 4—4 of Fig. 2; Fig. 5 is a face view of an addressing device in accordance with my application 703,899, carrying two of the same tabs; Fig. 6 is a fragmentary rear view of the addressing device of Fig. 5; Fig. 7 is an enlarged cross-section on the line 7—7 of Fig. 6.

The tab, designated A, is made of a single piece of thin somewhat resilient material preferably metal, and comprises an upper or visible portion 1 and a centrally downwardly projecting shank 2, preferably rounded at the lower end 3. Formed in the shank 2 is a tongue 4 integral with the shank near the lower end thereof but otherwise separated from the shank. As shown, this separation is effected by a narrow V-shaped slit 6. The tongue 4 normally lies in the plane of the shank, as shown, but may be readily diverted therefrom in either direction at an acute angle to such plane.

The tab-shank 2 has a width materially less than the head 1, so that the shank may be readily passed into strap-like keepers on a device to be indexed with the shoulders provided by the tab-head forming an abutment limiting the inward movement. The point of the tongue 4 when the tab is inserted coacts with the shoulder on the device to be indexed to form a temporary or releasable abutment to prevent the removal of the tab. This will be explained with reference to each of the addressing devices illustrated in the drawing.

Referring to Figs. 2, 3, and 4, I have shown the member B to be indexed as an addressed plate comprising essentially a sheet metal member 10, ordinarily called a frame or holder and a printing member 20 thereon, which may be a strip of sheet metal, embossed with printing characters 21. The holder also preferably carries a suitable index card 30. As shown, the printing plate 20 is held between the curled over lower edge 11 of the holder 10 and suitable lips 12 cut from the holder, and end stops 13, which may be on spring tongues 14 formed of the metal of the holder to enable the ready insertion, retention and removal of the plate. The index card 30 is shown as held by curled over upper lip 15 of

the holder and suitable lips 16 pressed up from the body of the holder.

- Formed by the material of the plate 10 is a row of keepers 40, which are in the plane of the plate 5 or very slightly above it. Each keeper comprises a strap separated above and below from the plate proper (which is relatively depressed in these regions) and connected at their ends by intermediate plate portions 41, which are bowed upwardly from the plane of the adjacent plate portions, being connected therewith above and below by gradual offsets. Thus, the strap portions form loops relatively raised from the portions of the plate immediately above and below them.
- Between the row of keepers 40 and the adjacent edge of the plate is one of the relatively depressed regions above mentioned, which comprises a horizontal zone 42, depressed from the plane of the plate, and at the top of this region are a series of openings 43 through the offset region where the zone 42 joins the body of the plate, adjacent the lower edge of the curled over edge 15. Below the various keepers 40 is an inclined region 45 of the plate which extends upwardly and backwardly from the face surface of the plate, the upper edge of the incline terminating in a horizontal line which is directly behind the horizontal line defining the lower edge of the keepers 40. This inclined portion forms the other relatively depressed region of the plate.
- It results from the above described construction that the plate or other member to be indexed has, along its upper portion, a row of pockets open at the upper end, each pocket having its admission through a slot 43, then a forwardly open portion in front of the zone 42, then a rearwardly open portion behind the keepers 40 and finally a forwardly open, but rearwardly closed, inclined portion 45.
- The pockets above-described and the shanks of my tabs are so mutually dimensioned that the shank may be readily inserted in any pocket and be positioned thereby. Accordingly, the shank 2 has a width only slightly less than that of any pocket and the thickness of the tab is only slightly less than the depth of the pocket, as bounded at the rear by the front face of the zone 42 and at the front by the rear face of the keepers 40.
- Now, when the tab is inserted, a peculiar action takes place. As soon as the lower end of the shank engages the incline 45 of the plate, the further shoving in of the tab bends the lower end forwardly by reason of the camming action of the plate and this projects the tongue rearwardly as illustrated in Fig. 4. When in this position, the end of the tongue stands directly in line with the offset body portion 42 of the plate. Accordingly, the tab cannot be drawn out when the tongue is in this position.
- It will be seen from the above description that the tab may be very readily inserted in place and when in place it becomes automatically locked by reason of the tongue being bent behind the retaining zone 42 of the plate. The tab is thus effectively held so that it will not be inadvertently removed either manually or by the action of the selector mechanism coacting with a tab, in an address printing machine. However, the tab may be released whenever desired by a slight manual pressure; as, for instance, by the user's thumb nail against the tongue 4 at the rear side of the plate. As shown in Fig. 3, the space behind the keepers 40 is open, and accordingly, the tongues 4 are readily accessible, and a

slight pressure against the tongue bends it back into the normal plane of the tab shank so that the tab may be very readily removed.

The addressing device C shown in Figs. 5, 6 and 7, is designed for direct embossing on the article itself rather than as a frame to hold a separate plate. Fig. 5 shows that face of the device which is against the paper during the printing operation, the opposite face (Fig. 6) being usually vertical and forward when the devices are stacked in a storage drawer. Describing the construction when the device lies horizontally with the face of Fig. 6 uppermost, the device includes a flat metal plate 50 having a face 51 in which the printing characters 52 are embossed downwardly, while there is a depressed region 54 of the plate which is formed with retaining means for the tab and card.

As shown in Figs. 6 and 7, a narrow index card 57 may lie on top of the keepers 56 with one edge 20 under the overturned edge 59 of the plate and the other edge beneath projections 60 in the plane of the plate. It will be understood that the card is intended to furnish a readily visible indication of some or all of the matter embossed on the 25 plate. The two card retaining edges 59 and 60 extend substantially the entire width of the plate, although the edge 60 is interrupted into a series of projections to provide for downwardly turned strip portions 65 of the plate, hereinafter de- 30 scribed.

The row of keepers 56 of the tab is behind the index card, as clearly shown in Fig. 7, and the interposition of the keepers between the tab and index makes it impossible for one to interfere with the 35 position of the other.

The strip portions 65 of the plate C, it will be noticed from Fig. 7, are at a slight angle to the face of the plate. It will be seen also from this figure that each keeper has a projection 67 ex- 40 tending from it toward the region to be occupied by the tab, this projection being preferably made by indenting the opposite face of the keeper, as illustrated.

With the addressing device as shown in Figs. 45, 5, 6, and 7, when the tab is slid into the pocket the end of the tab shank is guided along the inclined portion 65 which bends the tab. The point of flexure of the tongue to the tab is so located that as the plate portion 65 bends the 50 end of the tab, this action tends to force the tongue 4 away from the plate. At the same time, the projection 67 presses against the tongue 4 and forces it away from the plane of the keeper as soon as the point of the tongue clears the plate por- 55 tion 64.

Thus, under the combined action of the inclined surface 65 and the projection 67 on the plate C, the free end of the tab tongue comes into abutting relation with the edge of the depressed zone 64, thus locking the tab against removal until the tongue again is forced out of abutment with that portion.

The two forms of addressing device illustrated in the drawing show that my tab is adapted for 65 mounting in different forms of holders. The tongue may be diverted from its normal position either by bending the lower end of the tab or by the projection to engage the tongue or by the combined action of both incline and projection. 70

It will be seen that the tabs having the tongue normally in the same plane as the rest of the tab, possess a decided advantage over tabs having projecting bars or wings. My tabs may be more compactly stored; are not likely to become 75

tangled; may be used without possibility of injuring the operators' fingers; are insertable with either face forward into holders of various types, and are adapted for very cheap manufacture.

5 I claim:

1. An index tab comprising a strip having a head and a resilient tongue below the head and pointing toward it, said tongue normally lying in the plane of the strip but adapted to be caused 10 to project therefrom in use.

10 2. An index tab comprising a strip having a head and a spring tongue extending toward the head and normally lying in the plane of the strip but adapted to be positioned at an angle 15 thereto consequent upon the bending of the strip, said head providing a shoulder adapted to limit the inserting movement of the tab.

20 3. An index tab having a head and a shank, a resilient tongue comprising part of the material of the shank and attached at its lower end to the shank and projecting toward the head of the tab and free from the shank at the upper end of the tongue, the tongue lying normally in the plane of the shank.

25 4. An index tab comprising a thin strip of sheet material having a head and a shank materially narrower than the head, said shank being connected with the head by an abrupt transverse shoulder, and a spring tongue cut out of the shank so as to be free therefrom at its sides while attached thereto at its lower end and projecting upwardly toward the head and normally lying in 30 the plane of the shank, but adapted to be readily

bent at an upwardly facing acute angle to such shank.

5 5. An index tab comprising a thin strip of spring metal having a head and a shank, and an upwardly extending tongue cut out of the shank, 5 the lower end of the tongue uniting with the body of the shank and the tongue normally lying in the plane of the shank and having a length materially greater than its width, whereby the point of the tongue may stand entirely beyond 10 the side of the shank when the tongue is bent at a slight angle to the shank.

6. An index tab comprising a thin strip having a head and a parallel-sided shank materially narrower than the head connected with it by an abrupt shoulder, and a tongue cut out of the shank by a V-shaped opening piercing the shank mid-way between the side edges thereof with the apex of the V upward, the lower end of the tongue 15 uniting with the body of the shank and the tongue 20 normally lying in the plane of the shank and having a length materially greater than its width, whereby the point of the tongue may stand entirely beyond the side of the shank when the tongue is bent at a slight angle to the shank. 25

7. An index tab comprising a thin, flat piece of spring metal having a head and a resilient shank, and a tongue cut out from the shank connected at its lower end to the shank adjacent the lower end of the shank, said tongue normally lying 30 in the plane of the shank but being adapted to project from either face thereof when the lower end of the shank is bent.

WALTER T. GOLLWITZER.
